UNITED STATES PATENT OFFICE.

EMMETT W. STULL, OF NORWOOD, OHIO, ASSIGNOR TO ALLIS-CHALMERS COMPANY, A CORPORATION OF NEW JERSEY, AND THE BULLOCK ELECTRIC MANUFACTURING COMPANY, A CORPORATION OF OHIO.

CONTROLLER.

No. 873,805

Specification of Letters Patent.

Patented Dec. 17, 1907.

Application filed March 31, 1906. Serial No. 309,027.

To all whom it may concern:

Be it known that I, EMMETT W. STULL, citizen of the United States, residing at Norwood, in the county of Hamilton and State of Ohio, have invented certain new and useful Improvements in Controllers, of which the following is a full, clear, and exact specification.

My invention relates to controllers for electric motors and particularly to motor controllers for electric railway work.

One of the objects of my invention is to prevent the sparking or destructive arcing which often occurs between the fingers of the controller, and renders the fingers unfit for further use.

Another object of my invention is to concentrate and properly direct the lines of force from the blowout magnet at the desired points, and to diminish the reluctance of the magnetic blowout circuit.

Another object is to provide a more efficient arrangement of blowout coils.

A further object is to prevent any arc which may be formed between the fingers from running or drawing back from the contacting ends of the fingers toward their supports. This has heretofore been a serious defect in controllers, for when the arc had thus drawn back it was out of the field of the blowout magnet, and had nothing to hinder it from entirely destroying that part of the controller.

A still further object is to prevent improper handling of the controller by providing a novel interlocking arrangement between the controlling drum and the reversing switch so that the latter can be moved only when the former is in a predetermined or "off" position, and, if desired, so that the former cannot be moved when the latter is in a predetermined, neutral or "off" position.

My invention in one of its aspects consists of a novel arrangement for preventing sparking or destructive arcing at the controller contacts. This I accomplish by providing a plurality of blowout magnets magnetically in parallel and supplying a common magnetic circuit, the ends of the magnet cores

50 forming bearings for the controller drum.

It also consists in the use of the shaft of the controller drum as a part of the magnetic circuit, and the proper directing and concentrating of the lines of force at the de-

sired circuit-breaking points of the controller 55 and the diminishing of the reluctance of the blowout magnetic circuit by inserting plugs of magnetic material in the controller drum adjacent to such points, which plugs serve as separate and individual pole-pieces for the 60 blowout magnets and as polar projections or extensions from the shaft of the controller drum. This feature may be used alone, or in combination with another feature, which consists in including part of the controller 65 casing in the blowout magnetic circuit, and having, as separate and individual pole pieces, paramagnetic extensions from the casing to points in proximity to the arcing or circuit-breaking points of the controller, 70 thereby better directing and concentrating the magnetic lines of force at the desired points and still further diminishing the reluctance of the blowout magnetic circuit.

My invention also prevents any arcs which 75 may form between the fingers from drawing back along the fingers toward their supports. This is accomplished by means of a screen or shield of insulating refractory material between the supports for the fingers and the 80 points where the fingers make contact with the controlling drum.

Another feature of my invention is the enclosing of the controller drum and the points of arcing in a box or casing of insulating re- 85 refractory material.

My invention in another of its aspects consists of a controller provided with a plurality of spring pressed arms coacting with the controlling drum and the reversing switch to 90 control the movement of the latter, and if desired, of the former also.

Considered in a more specific aspect my invention comprises a controller in which there are two spring pressed arms coacting with 95 the notch plates of the controlling drum and the reversing switch respectively to prevent movement of the reversing switch except in a predetermined or "off" position of the controlling drum, and if desired, to prevent 100 movement of the controlling drum in a predetermined, neutral or "off" position of the reversing switch.

Other features of my invention will more clearly appear in the following specification 105 and the accompanying drawings, and will be specifically pointed out in the appended claims.

Figure 1 is an elevation of my improved controller with the front half of the controller casing removed, and with some of the parts in section. Fig. 2 is a plan view of the controller with the cover and handles removed, showing the interlocking arrangement between the controller drum and the reversing switch. Fig. 3 is a horizontal section on the line 3—3 of Fig. 1 and shows the general arrangement of the blowout magnetic circuit. Fig. 4 is an elevation of part of the front half of the controller casing looking from the inside and with the arc deflector plates removed. Fig. 5 is an elevation of the arc deflector plates of the controller, and, Fig. 6 is a detail showing one of the plugs of magnetic material in the controller drum.

In the drawings A is the controller drum, movable by the usual handle A' and provided with contacts B with which the spring contact fingers C coact to vary the connections between the supply circuit and the controlled devices, which may be electric motors. The drum A is mounted on but insulated from a shaft D of iron or other magnetic material. Surrounding the drum is a box or casing E, E', E² of insulating and refractory material such as prepared asbestos which may be covered with mica. The parts E and E² of this box or casing are fastened in place on the main controller, the part E forming a screen or shield between the circuit-breaking points of the controller and the supports for the contact fingers. The part E' is mounted on the front part G' of the main controller casing. The spring contact fingers C are mounted on a support F on the outside of the shield E, the fingers being adjustable by the screws C'. The fingers C extend through holes or openings e in the shield E into proximity to the controller drum so that proper engagement between the fingers C and the contacts B may be made when the drum is rotated. Should any arc form between adjacent fingers and attempt to run back along the fingers towards their supports, the shield or screen E through which the fingers extend and which is in the path of the arc will act to cool and thereby break said arc. Thereby destructive and dangerous arcing between the fingers is avoided. If desired, instead of having the fingers C extend through openings in shield E, they may extend around the edge of said shield, though with such an arrangement, the absolute prevention of the drawing back of the arcs would not be secured.

The main controller casing is formed in two parts, a back part G of iron or other magnetic material, and a front part G' of wood or other insulating material, and has a cover W of brass or other non-magnetic material. As shown in Fig. 3, the front part G', which is nearest the operator, is made of tongue and groove boards fastened together and

strengthened by metallic bands q at the top and bottom, both inside and outside. Extending from the iron part G of the controller casing are two cores H H on which are placed coils I I to form blowout magnets. These coils may be connected in any desired manner. From the cores H H and fastened thereto in any desired manner as by screws h project extensions H' H' which serve not only as paths for the magnetic flux but also as bearings for the iron shaft D of the controller, drum. This controller, shaft also forms part of the magnetic circuit for the two blowout magnets, which are so wound as to make the extensions H' H' of the same polarity. Plugs K of iron or other magnetic material are embedded in the controller drum A and extend inward nearly to the insulation around the iron shaft D of said drum and outward toward the contacts B, but are not mounted on and do not touch the shaft itself. These plugs are located so as to be just beneath the circuit-breaking points of the controller or the points where the contact fingers C leave the contacts B and are riveted to small plates K' also of magnetic material, these plates serving to spread out the magnetic field across the whole width of the contact finger. The plates and attached plugs are removably fastened to the contact segments B, as by screws k. These plugs therefore are common pole pieces of the two blowout magnets, and serve individually to concentrate and direct the lines of force at those points respectively where arcing is liable to occur and collectively to diminish the reluctance of the magnetic circuit.

For still better directing and concentrating the lines of force at the proper points, and further diminishing the reluctance of the magnetic circuit, strips of iron may be mounted inside of the front half G' of the controller casing, which when this casing is in place bear against the back half G of the casing and are practically magnetically continuous therewith. For better insulation the ends of the strips L are protected by insulation l'. These strips extend from the iron part of the casing, which is part of the blowout magnetic circuit, around the inside of the wooden part of the casing until they are over the ends of fingers C. At l' they are bent inwardly to bring them nearer the ends of fingers C. These strips are the other common pole-pieces of the blowout magnets, of opposite polarity to the plugs K. Thus as shown in Fig. 3 the breaking of the circuit between fingers C and contacts B occurs in a strong magnetic field between the ends of strips L and the plugs K. This field is excited by the two coils I I magnetically in parallel, and the path of the flux is from the cores H H to the casing G, strips L, across the air gaps to plugs K, shaft D, extensions H' H' to cores H H. The only gaps of any

length in this divided paramagnetic path are those between the strips L and the plugs K, in which gaps the circuit breaking takes place. There is one strip L for each finger C 5 and there may be plugs K at each end of each contact B as shown in Fig. 3, so that the proper blowout action may be obtained at the circuit breaking points in whichever direction the controller drum is rotated. The 10 various contacts B are arranged in any desired manner around the shaft D, the connections and arrangements of these contacts forming no part of my present invention.

Extending from the part E' of the insulating box around the controlling drum are plates T of insulating and refractory material, such as asbestos covered with mica. These plates are spaced apart by insulating tubes t, the whole being held together by 20 bolts t', shown as three in number, passing through the tubes and the plates. These plates when in place extend inwardly between each contact finger and the adjacent ones, one being shown in Fig. 3 below the 25 contact finger C, thus serving to prevent the arc from one contact finger from striking over to another finger. These plates are fastened together and to the plate E' as shown in Fig. 5 and are placed against the 30 inturned ends of strips L on the inside of the front half G' of the controller casing as shown in Fig. 3, being spaced from the casing by bushings U and the strips L. This set of plates may be held in place by any desired 35 means as by bolts.

In the right hand side of the controller casing is a reversing switch M of any desired type and movable by the handle M'. On the shaft of the reversing switch is a notch plate 40 N and on shaft D is a notch plate O. These notch plates are placed near the upper ends of their respective shafts. Pivoted to the casing G are two arms P and Q carrying rollers p and q at their free ends. These rollers 45 engage the notch plates N and O respectively. The two arms P and Q are in the same plane and are preferably thrust apart by a spring R. One of the arms Q carries a projection S arranged to engage with the 50 other arm P whenever an attempt is made to move the reversing switch while the controlling drum is not in "off" position, and if desired, whenever an attempt is made to move the drum while the reversing switch is in 55 "off" position. In Fig. 2 the controlling drum and the reversing switch are both shown in "off" positions. The reversing switch can now be moved to either forward or backward position. The length of the 60 projections may be such that on an attempt to rotate the drum with the reversing switch in neutral or "off" position, the roller q leaves notch o in notch plate O before the projection S engages P, and in such a case the 65 drum could be rotated with the reversing

switch in any of its three positions. But preferably the length of the projection S is such that by its engagement with the arm P while the roller q is still in notch o, the drum is prevented from rotation while the reversing 70 switch is in the position shown in Fig. 2. However, in either construction, if the reversing switch is moved either to forward or backward position so that the roller p is in either of notches n or n', the drum can be 75 moved freely. But if the drum is moved out of "off" position, the roller q rides on the periphery of notch plate O, and arm Q and projection S move toward the right. When this is the position of the parts, the reversing 80 switch is locked against movement, for on attempting to move it, arm P engages projection S before the roller p can pass over shoulder N' and thereby further movement of the reversing switch is prevented. Thus 85 it is impossible for the reversing switch to be thrown except when the controlling drum is in "off" position.

Although I have described my invention in its preferred form, it is obvious that many 90 equivalents of the various parts shown and described may be used without departing from the spirit and scope of my invention, and therefore I do not wish to be limited to the exact structure shown and described, 95 but set up in my claims the broad novel features invented by me.

I claim:

1. In a controller, a controlling drum, a shaft of magnetic material therefor, a blow-out magnet outside of the drum and having the controller shaft as part of the magnetic circuit, and plugs of magnetic material inserted in said drum. 100
2. In a controller, a controlling drum, a shaft of magnetic material therefor, a blow-out magnet not concentric with the drum and having the controller shaft as part of the magnetic circuit, and plugs of magnetic material inserted in said drum adjacent to the 110 points where arcing is liable to occur. 105
3. In a controller, a controlling drum, a shaft of magnetic material therefor, a plurality of blowout magnets not concentric with the drum and having the controller shaft as part of the magnetic circuit, and plugs of magnetic material inserted in said drum adjacent to the 115 controlling drum. 115
4. In a controller, a controlling drum, a shaft of magnetic material therefor, a plurality of blowout magnets outside of the drum and having the controller shaft as part of the magnetic circuit, and plugs of magnetic material inserted in said controlling drum adjacent to the circuit-breaking points 125 of the controller. 120

5. In a controller, a controlling drum, a shaft, radial pole-pieces carried by said drum adjacent to the ends of the contact segments of the drum, and a plurality of coils for mag- 130

netizing said pole-pieces, said coils being energized whenever current is flowing through the controller.

6. In a controller, a controlling drum, a shaft of magnetic material therefor, a blow-out magnet having the controller shaft as part of its magnetic circuit, and radial pole-pieces carried by said drum adjacent to the ends of the contact segments of the drum.

10. 7. In a controller, a controlling drum, a shaft of magnetic material therefor, a casing of magnetic material for the controller, a blow-out magnet having the controller shaft and the casing for parts of its magnetic circuit, extensions from said casing to points adjacent to and on one side of the arcing points of said controller, and plugs of magnetic material in the drum on the opposite side of said arcing points.

20. 8. In a controller, a controller drum, a shaft of magnetic material therefor, a casing of magnetic material for the controller, a plurality of blowout magnets having the shaft and the casing for parts of their magnetic circuits, and plugs of magnetic material in said drum near the circuit-breaking points of the controller.

30. 9. In a controller, a controller drum, a shaft of magnetic material therefor, a casing of magnetic material for the controller, a plurality of blow-out magnets having the shaft and the casing for parts of their magnetic circuit, extensions of magnetic material from said casing to points adjacent to and on one side of the arcing points of said controller, and plugs of magnetic material in said drum on the opposite side of said arcing points.

35. 10. In a controller, a controlling drum, a

shaft of magnetic material therefor, pole pieces adjacent to said shaft, said pole-pieces being mounted in said drum and insulated from said shaft, and a blowout magnet for magnetizing said pole-pieces.

40. 11. In a controller, a controlling drum, contact fingers coacting therewith, a support for said fingers, and a shield of refractory material between said support and said drum, said fingers extending through the shield.

45. 12. In a controller, a controlling drum, contact fingers coöperating therewith, a support for said fingers, a casing of insulation surrounding said drum and between said drum and said support, said casing being provided with openings through which the fingers project.

50. 13. In a controller, a controlling drum, a casing of insulating material surrounding said drum, a blowout magnet, extensions from one end of said magnet core to points on the outside of said casing adjacent to the arcing points of the controller.

55. 14. In a controller, a controller drum, a casing of refractory material surrounding the drum, a plurality of blowout magnets, a main controller casing forming common part of the magnetic circuit for said blowout magnets, polar extensions from said main casing to points on the outside of said refractory casing and adjacent to the arcing points of the controller.

60. In testimony whereof I affix my signature in the presence of two witnesses.

EMMETT W. STULL.
